UNITED STATES PATENT OFFICE.

FRANK E. ROBERTS, OF LYNN, MASSACHUSETTS, ASSIGNOR, BY DIRECT AND MESNE ASSIGNMENTS, TO GOTHAM PROCESS SHANK, INC., A CORPORATION OF MASSACHUSETTS.

BOOT AND SHOE.

1,370,363.

Specification of Letters Patent.

Patented Mar. 1, 1921.

Application filed August 20, 1919. Serial No. 318,771.

To all whom it may concern:

Be it known that I, FRANK E. ROBERTS, a citizen of the United States, residing at Lynn, in the county of Essex and State of Massachusetts, have invented certain new and useful Improvements in Boots and Shoes, of which the following is a specification.

My invention relates to boots and shoes and has reference particularly to the construction and method of making the soles thereof.

It has been the practice to mold the outer- soles of boots and shoes, particularly women's boots and shoes, so as to form a sharply defined angle or corner extending across the sole at the junction of the shank with the fore-part, that is, just back of the ball of the foot, so as to give a pronounced arch to the shank that starts upwardly abruptly from the rear end of the fore-part. Also it has been common to mold the shank of the outersole so that it was of flattish V-shape in cross-section with a medial ridge or corner upon the exterior thereof extending from the first mentioned corner or angle at the rear of the fore-part to the breast of the heel. This peculiar molding of the outersole has the advantage of improving the appearance of the boot or shoe and also of stiffening the shank.

Heretofore the outersole has been molded to this shape by means of dies before incorporation in the shoe and while the sole was in the form of a more or less rectangular blank. After being thus molded the sole blank was placed in position on the lasted innersole and upper, sewed in place and trimmed. Because of the fact that the sole was in the form of an untrimmed blank and hid the upper and innersole from view when placed in position upon the latter, it was impossible for the shoemaker to accurately position the sole, particularly the shank portion thereof, so that it very frequently happened that it was misplaced and when the outersole was trimmed the medial longitudinal ridge of the shank would be positioned nearer one side of the shoe than the other which was highly objectionable. Another objectionable feature was that outersoles molded in this fashion before being applied to the shoe did not hold their molded shape as long as desirable.

My invention has for its object to im-

prove the construction of boots and shoes of the class described and to provide a new method of making boots and shoes of this kind. Also, it is the object of my invention to obviate the above noted objectionable features of the construction and method of making boots and shoes of this kind heretofore employed.

The invention consists of a boot or shoe of the character described having the peculiar features of construction set forth in the following description and particularly pointed out and defined in the claims at the close thereof. The invention further consists of the new method hereinafter set forth and claimed of making boots and shoes of the class described.

In the accompanying drawings:

Figure 1 is a perspective view of a woman's shoe constructed in accordance with my invention.

Fig. 2 is a perspective view of a woman's shoe constructed in accordance with my invention, but illustrating additional features of the latter.

Fig. 3 is a perspective view of the fore-part of the outersole showing my new bolstering member in place thereon.

Fig. 4 is a section on line 4—4 of Fig. 2.

Fig. 5 is a perspective view of one form of bolstering member employed by me.

Fig. 6 is a perspective view of another form of bolstering member.

Fig. 7 is a perspective view of a bolstering member of another kind.

Having reference to the drawings, 1 represents the upper of a Goodyear welt shoe, 2 the welt, 3 the innersole, 4 the outersole, and 5 the usual shank stiffener.

In manufacturing a shoe of the kind shown, the upper, innersole and welt are assembled on the last and sewed together and then the outersole in the form of an untrimmed blank is placed in position by the operator and sewed to the welt. In preparing the outersoles for shoes of this kind the more or less rectangular blanks are "tempered" and molded to shape between dies, the sole being bent transversely and sharply at the junction of the shank with the fore-part so as to provide a sharply defined angle or corner extending somewhat obliquely across the sole at the rear of the forepart as indicated at 6 in Fig. 1. Sometimes, also, the shank 7 is molded by the dies so as to

make it V-shaped in cross-section with a sharply defined medial ridge 8 upon its exterior extending from the corner or angle 6 to the breast of the heel. This method of construction was objectionable for the reason that it was practically impossible for the shoe maker to accurately position the outersole so that the fold or corner 6 would occupy its proper position with relation to 10 the ball of the shoe, and so that the ridge 8 would occupy its proper position midway between the side edges of the shank when the outersole was trimmed. Moreover, this old method of construction left cavities between the outersole and innersole, particularly beneath the ridge 8 so that after comparatively short use the sole would lose its molded shape.

In constructing the shoe of Fig. 1 the upper and innersole are lasted and sewed together as usual after which the usual filler 10 is spread over the fore-part of the innersole between the edges of the upper. Next place upon the innersole, immediately 25 at the rear of the filler 10, a bolster member 9, Fig. 3, said bolster extending more or less obliquely across the sole at the rear of the fore-part thereof. An unmolded outersole blank is then placed in position 30 and sewed to the upper and welt in the usual fashion after which the outersole is trimmed. The outer sole is then beaten down, this beating down usually being effected by subjecting said sole to the action 35 of a shaping machine. When the outersole is thus beaten down it is not only shaped to the last but also bent or folded sharply around the bolster member 9, the latter producing a sharply defined bend or 40 corner 6 upon the exterior of the sole corresponding in shape and position to the shape and position of the bolster member. It will thus be seen that a distinguishing 45 feature of my invention consists in incorporating in the shoe between the innersole and the outersole, means for effecting the shaping or molding of the outersole when the latter is beaten down against the last, and as will be clear the advantage to this 50 is that the bend or corner 6 can be accurately positioned and shaped as desired.

When it is desired to form the shank of the outersole with a medial ridge extending from the bend or corner 6 to the breast of the heel, as in Fig. 2, another bolster in the form of a stem 11 is placed in position on the shank of the innersole lengthwise of the latter and midway between the side edges thereof, said bolster 11 being curved 60 or bent longitudinally to accord with the arch of said shank, and of a length to extend from the bolster 9 to the breast of the heel. When the outersole is beaten down the shank portion thereof is given a V-shape 65 in cross-section displaying a sharply de-

fined ridge at the middle of the shank, extending from the bend or corner 6 to the breast of the heel as shown in Figs. 2 and 4.

When the shoe, constructed in accordance with my invention, is subjected to use the bolster and outersole shaping members 9 and 11 serve to support the outersole at the corner 6 and ridge 8 so that those parts of the sole keep their shape much longer 75 than heretofore.

The shaping bolsters 9 and 11 may be made from any suitable material but preferably of some pliable material which can be bent to the desired shape and which is 80 somewhat yielding or compressible as rubber. In practice I have found ordinary electric light wire made from copper and covered with rubber insulation to be an excellent material from which to make these 85 bolsters and in the drawings I have shown the same as made from this material. When made from covered wire of this sort the copper wire 12 is easily bent to the desired shape, being pliable but not springy 90 or resilient so that it holds the shape given to it. At the same time the relatively thick covering 13 of rubber or the like prevents injury to the outersole when the latter is beaten down to shape and at the same time 95 supports the sole sufficiently against the beating down pressure to effect the desired molding thereof.

The two bolster members 9 and 11 may be 100 separate pieces of wire as shown in Fig. 6, or if desired, the two may be united by fusing or cementing the end of the covering 13 of member 11 to the covering 13 of member 9 near the middle of the latter as shown in Fig. 7.

What I claim is:

1. The method of making boots and shoes of the class described which consists in first assembling the upper and innersole upon a last; then placing a bolstering member in position upon the innersole immediately at the rear of the fore-part of the latter; then securing the outersole in place, and lastly, beating down the outersole so that the bolstering member is utilized to shape the said 115 outersole.

2. The method of making boots and shoes of the class described which consists in incorporating an outersole shaping member in the boot or shoe between the innersole and the outersole while those parts are being assembled on a last, and thereafter beating down the outersole so as to cause said member to shape said outersole.

3. The method of making boots and shoes of the class described which consists in incorporating an outersole bolstering member in the boot or shoe between the innersole and the outersole while those parts are being assembled on a last, said member being pos-

- tioned immediately at the rear of the fore part of the boot or shoe, and thereafter beating down the outersole so as to cause said member to shape said outersole.
5. 4. The method of making boots and shoes of the class described which consists in incorporating an outersole bolstering member in the boot or shoe between the innersole and the outersole while those parts are being 10 assembled on a last, said member being positioned immediately at the rear of the fore-part of the boot or shoe and extending cross-wise thereof, and thereafter beating down the outersole so as to cause said member to 15 produce a sharply defined bend in said outersole extending across the latter at the rear of the forepart.
5. The method of making boots and shoes of the class described which consists in incorporating outersole bolstering and shaping means in the boot or shoe between the innersole and the outersole while those parts are being assembled on a last, said means extending across the boot or shoe at the rear 25 end of the fore-part and lengthwise of the shoe from the rear end of the fore-part to the breast of the heel, and thereafter beating down the outersole so as to cause said means to produce a sharply defined transverse bend 30 at the rear end of the fore-part of said outersole and give to the shank of said outersole a V-shape in cross-section with a sharply defined median ridge upon the exterior thereof.
35. 6. A boot or shoe of the class described comprising an innersole; an outersole, and outer sole bolstering means between said soles for imparting a definite shape to the outersole when the latter is beaten down, said bolstering means producing a sharply defined bend in said outer sole.
7. A boot or shoe of the class described comprising an innersole; an outersole, and a bolstering member consisting of a length 40 of pliable metal wire having a covering of 45 rubber or the like, said bolstering member being arranged between said two soles and extending transversely thereof so that when the outersole is beaten down said member causes a sharply defined bend to be produced 50 in said outersole extending along the line of junction of the fore-part of said outersole with the shank thereof.
8. A boot or shoe of the class described comprising an innersole; an outersole; and 55 outersole shaping means arranged between said two soles consisting of a length of pliable metal wire having a covering of rubber or the like and disposed crosswise of said outersole along the line of junction of the 60 fore-part and shank thereof, and a length of pliable metal wire having a covering of rubber or the line disposed lengthwise of 65 said outersole at the middle of the shank of the latter and extending from said first mentioned length of wire to near the breast of the heel of the shoe, said lengths of covered wire serving to shape the outersole when the latter is beaten down.
9. A boot or shoe of the class described 70 comprising an innersole; an outersole; a bolstering member arranged between said soles and extending transversely thereof along the line of junction of the fore-part of the outersole with the shank thereof to produce a 75 sharply defined bend in said outersole along the line of said junction when the outersole is beaten down, and a bolstering member arranged between said soles and extending along the middle of the shank of the outersole from said first mentioned member to the 80 breast of the heel of the shoe to produce a sharply defined median ridge upon the exterior of said shank.
- Signed at Lynn in the county of Essex 85 and State of Massachusetts this 9th day of August, 1919.
